DISPENSING UNIT

Lloyd B. Whittaker, New York, N. Y.

Application March 4, 1935, Serial No. 9,195

2 Claims. (Cl. 128—231)

This invention relates to dispensing units and has as its object a tubular dispensing unit holding a quantity of a dispersible substance, such as a medicinal fluid or cream, which is to be applied to an interior part of the body, and permitting direct discharge and dispersion of its contents at the point of application without danger of contamination by foreign substances.

The foregoing and other objects of the invention will be understood from the following description of an exemplification thereof, reference being had to the accompanying drawing, in which

Fig. 1 is a sectional view of a complete dispensing unit embodying the invention;

Fig. 2 is a dispensing unit with its outer covering removed and equipped with a bulb for dispensing its contents; and

Figs. 3 and 4 are views showing the dispensing unit at different stages of its preparation.

In accordance with the invention, a dispersible substance, such as a medicinal fluid or fluffy preparation, that is to be applied to delicate internal parts of the human body, such as the mouth cavity or nasal cavity of a person, is enclosed in a tubular container which permits direct discharge of its contents at the point of its application within the cavity of the body, the exterior parts of the container which come in contact with delicate interior parts of the body being kept in clean and sanitary condition and its contents being sealed and protected against contamination by a removable flexible coating enclosing the discharge portion of the container.

As shown in Fig. 1 the dispensing unit comprises a cylindrical tube 10 of glass or similar material having at its front end a restricted discharge opening 11 and at its rear end an impelling opening 12, the tubular vessel containing a dispersible substance 13, such as a medicinal fluid or fluffy cream, which is to be applied to an accessible internal body portion of a person. The substance is held tightly sealed within the container by means of a cylindrical plug 14 at the impelling opening of the tube and a tubular coating 15 of a flexible substance, such as rubber, which seals the discharge opening 11 and extends lengthwise the tube to cover the part of the tube that is inserted into the cavity where it is to be applied. The plug 14 may be made of a plurality of layers of cotton felt saturated with a filler, such as a mixture of petrolatum and melted wax. The impelling opening and the adjacent rear end of the tube may be likewise enclosed by a flexible coating 17, of rubber, like the front portion of the tube. The two rubber coatings 15 and 17 are

under tension and cling to the exterior of the tube 10, sealing up its interior and protecting the exterior of the tube against contamination. If required, by the consistency of the substance, the discharge opening 11 may be sealed with a readily removable plug 19 of sealing material, such as paper or rubber, before the coating 15 is placed thereon.

The plug 14 which encloses the impelling opening of the tube 10 clings tightly to the inner walls 10 of the tube to seal its contents, and has a fit which permits it to move quickly as a piston to the front end of the tube for discharging the substance 13 through discharge opening 11 when impelled by air pressure produced by means of a small rubber bulb attached to the impelling opening 12 of the tube.

The fluid dispensing unit may be readily discharged and dispersed at any desired point in the mouth cavity or any other cavity of the body by removing the flexible coatings 15 and 17 from the tube 10 and slipping a rubber neck 21 of a rubber bulb 22 over the rear end of the tube 10. The unit is then inserted into the cavity so that its discharge opening 11 faces the interior body portion to which it is to be applied, and by squeezing the bulb 22 the plug 14 is impelled by the compressed air from the bulb, the plug 14 acting as a piston and quickly discharging the fluid as desired.

In making the dispensing unit shown in Fig. 1, I preferably proceed as follows: Into a tube 10, which is clean on the inside as well as on the outside, is inserted through the rear opening 12 a plug of fluffy soft cotton felt and the plug is driven to the forward end of the tube 10 where it rests against the discharge opening 11. A mixture of petrolatum and melted wax is then injected through the opening 11 into the felt plug 14 until it is fully saturated with the mixture. The plug 14 then forms a piston fitting the tube and able to slide in sealing engagement with the tube to its rear position. The substance 13 with which the tube 10 is to be filled is then injected through the front opening 11 of the tube, and under the pressure of the injected substance the plug 14 moves to its rear position as shown in Fig. 4. If required, the discharge opening is then plugged up by a layer of paper or rubber 19, and the front part of the tube 10 dipped into a bath 50 of latex which adheres to the glass tube. On removal from the bath, the latex adhering to the dipped portion of the tube forms the coating 15, sealing the discharge opening 11 and covering the exterior of the tube, protecting it against 55

contamination. By repeating the dipping process, a coating 15 of any required thickness may thus be made.

5 A coating 17 over the rear end of the tube 10 may be formed in a similar way by dipping the tube in a latex bath. Since the rear end of the tube does not come in contact with any body portions, the plug 14 forms a sufficient air tight seal protecting the fluid in the interior of the

10 tube.

Other ways of applying the invention in the way defined by the claims will suggest themselves to those skilled in the art.

I claim:

15 1. A medication unit for storing a dispersible medication substance in sanitary condition and directly discharging the medication substance at its point of application comprising an elongated tubular casing of uniform cross-section having a
20 discharge opening at its front end, a plug member of a porous flexible fabric fitting into the rear end of said casing, the entire body of said plug member being saturated with a gas tight sealing substance clinging to the walls of said casing
25 and sealing the rear end of said casing, and an expellable medication substance filling the space within said casing between said discharge open-

ing and said plug member, said plug member constituting a piston adapted to be impelled by air pressure applied to the rear end of said casing through the length of said casing for expelling said medication substance through said discharge opening, and a detachable elastic coating clinging to said casing walls and constituting an enclosure sealing said discharge opening and a substantial length of said casing walls.

2. The method of preparing a medication unit 10 suitable for storing a dispersible medication substance and discharging the stored substance at its point of application which comprises positioning at the discharge end of a tubular casing a plug of a porous flexible fabric, impregnating 15 said plug with a fluid substance which saturates said porous fabric and constitutes with said fabric a gas tight seal for said casing, injecting through said discharge opening a fluid medication substance for forcing said plug to the rear 20 end of said casing while filling said casing with said medication substance, and dipping a substantial length of the discharge end of said casing in a fluid forming a detachable coating clinging to the exterior of said casing and sealing the 25 discharge end thereof.

LLOYD B. WHITTAKER.
